MONITORING AND DETECTION CIRCUITS FOR SPUN FILAMENTS

Ronald Horne and George B. Price, Pensacola, and Robert D. Taylor, Milton, Fla., assignors, by mesne assignments, to Monsanto Company, a corporation of Delaware

Filed Feb. 13, 1961, Ser. No. 88,952

1 Claim. (Cl. 340—259)

This invention relates to monitoring circuits and more particularly to circuits for monitoring the denier of spun filaments.

In the manufacture of spun filaments it is of utmost importance that the denier or diameter of the filaments be uniform. Variations in denier will considerably lower the quality of the yarn, since these variations will be visible in the finished fabric. One of the causes of denier variations is fluctuations in the pressure applied to the spinning solution in the spinning head. A drop in pressure behind the spinnerette will result in a reduction in the diameter of the spun filaments. This is commonly called spinnerette "starvation."

In one type of spinning operation, commonly known as "melt" spinning, the filaments leave the spinnerette and pass downward through a chimney to rolls which advance the filaments to a takeup device. A stream of air is directed transversely across the chimney to cool and solidify the filaments. The embodiment of the invention disclosed herein monitors the denier of the filaments passing through the chimney. Thus, a denier variation is detected at once. In conventional spinning operations samples of the filaments are taken and measured for denier. The disadvantage of this method of inspection is that many yards of undersize yarn may be produced before the defect is detected. Of course, all of this yarn will be of very poor quality and may even be unusable.

One of the objects of this invention is to provide a novel and improved monitoring system.

Another object of this invention is to provide a system for monitoring spun filaments to detect denier variations therein.

A further object of this invention is to provide a system for automatically and continuously monitoring the denier of spun filaments at the spinnerette.

Still another object of this invention is to provide a circuit which operates an alarm or control in response to a decrease in denier of spun filaments.

One embodiment of the present invention contemplates a monitoring system wherein a light beam is projected across a spinning chimney onto a sensitive light-responsive resistor which is connected in a monitoring circuit. If the proper pressure is maintained behind the spinnerette the filaments will be of proper size and the air stream will sweep these filaments toward one side of the chimney to keep them out of the light beam. If, however, the pressure behind the spinnerette drops, the diameter of the filaments will decrease and one or more of the filaments will move into the light beam. This causes a variation in the resistance value of the light-responsive resistor to trigger the monitoring circuit which operates an alarm or control.

Other objects and advantages of the invention will become apparent when the following detailed description is read in conjunction with the appended drawing, in which the single figure illustrates one embodiment of the invention and shows a schematic diagram of the monitoring circuit and a fragment of the spinning chimney.

Referring now in detail to the drawing, fragments of a spinning head 11 and a spinning chimney 12 are shown. Filaments 14 are formed when a molten spinning solution is forced under pressure through the holes in the spin-

2

nerette (not shown) held within the spinning head. A stream of air from a nozzle or manifold 17 connected to an air source 18 is directed laterally across the spinning chimney to cool and completely solidify the filaments 14.

5 These filaments then pass between guide pins 19 and are taken up at a constant speed by well known equipment (not shown).

If the pressure in the spinning head 11 is at the proper value the spinning solution will be forced through the

10 spinnerette holes at a high enough speed to provide a slight amount of slack in the filaments 14. This slack will allow the air stream to deflect the filaments from a straight path, as illustrated in the drawing. If however, the spinning head pressure drops, the solution will pass

15 through the spinnerette holes at a slower rate. This will cause the takeup mechanism (not shown) to pull the filaments back onto a straight path and into alignment with a pair of slits 22 and 23 in the spinning chimney. Because of the constant speed takeup and the slower rate of passage of the solution through the spinnerette holes, the

20 denier of the filaments 14 will be decreased. Thus, a decrease in denier is accompanied by a movement of the filaments from the deflected path to a straight path.

A light source 26 positioned adjacent to the slit 22 directs a light beam laterally across the spinning chimney, through the slit 23 and onto a sensitive cadmium-sulphide resistor 27 of a well known type which varies in resistance in response to variations in the intensity of the light beam.

30 The cadmium-sulphide resistor 27 is connected between terminals 28 and 29 in series with a 2000 ohm potentiometer 33 and a 51K resistor 34, all three of these elements being connected in parallel with a series connected 100 ohm resistor 37 and transistor 38 connected between the terminals 28 and 29.

35 The base of the transistor 38 is connected to the tap of the potentiometer 33, while the transistor emitter is connected to the 100 ohm resistor 37. The collector of the transistor is connected through a normally closed, manually operated, switch 41 to the terminal 29.

A battery 42 is connected in series with a relay 43 between the terminals 28 and 29 for applying power to the circuit. The relay 43 is provided with a contactor 46 which is closable to connect an alarm lamp 47 to a battery when the relay 43 is pulled in, the relay 43 pulling in at 2.4 ma. and dropping out at 2.2 ma.

40 In operation of the monitoring system, the filaments normally follow the path shown in the drawing and the intense light beam holds the resistance of the light-responsive resistor 27 to a low value. The transistor will not be conductive. A small amount of current will flow through the circuit path which includes the relay 43 the 51K resistor 34, the potentiometer 33 and the light-responsive resistor 27. However, this current will not be great enough to pull in the relay 43.

45 In the event of a pressure drop in the spinning head, the filaments 14 will assume a straight path and will partially block off the light from the source 26. This causes an increase in the resistance value of the variable

50 resistor 27 which in turn causes the transistor 38 to become conductive. This allows more than 2.4 ma. to flow through the relay 43, thereby pulling in this relay to close the contactor 46 to connect the battery 48 to the alarm lamp 47. This indicates to the operator that the

55 spun filaments are not up to the desired quality so that he can begin an immediate check of the spinning apparatus to determine what has gone wrong. If it is desired, the closing of the contactor 46 can be used to operate a control device of some sort. For example, a device for stopping the spinning operation could be substituted for the lamp 47.

The variable or light responsive resistor 27 is so sensitive that the movement of a single 3 denier filament into the light beam will cause the transistor to become conductive.

This system provides an immediate inspection of spun filaments, so that necessary corrections can be made at once rather than after a large amount of off-denier yarn has been spun. Also, this system provides an automatic inspection of all of the yarn rather than just short portions as is the case with conventional inspection.

It is to be understood that the embodiment disclosed herein is merely illustrative and that this embodiment may be altered or amended and that numerous other embodiments may be contemplated which will fall within the spirit and scope of the invention.

What is claimed is:

A system for detecting a decrease in denier of melt spun filaments, comprising a spinning chimney through which the filaments pass, said chimney having a pair of slits in the opposite sides thereof, a nozzle positioned adjacent to the chimney for directing a stream of air from the back of the chimney thereacross to sweep the filaments to the front of the chimney and in a direction normal to a line extending through said slits, a light source positioned adjacent to one of the slits for directing a beam of light along said line through said slits, a cadmium sulphide resistor positioned adjacent to the other slit for receiving said light beam, said resistor having a resistance value

5
